UNITED STATES PATENT OFFICE.

GEORGE F. BROWN, OF PHILADELPHIA, AND HAROLD VAN DUZEE, OF JENKINTOWN, PENNSYLVANIA.

VALVE-ESCAPEMENT FOR RESERVOIRS, TANKS, &c.

SPECIFICATION forming part of Letters Patent No. 508,162, dated November 7, 1893.

Application filed August 9, 1892. Serial No. 442,579. (No model.)

To all whom it may concern:

Be it known that we, GEORGE F. BROWN, residing at Philadelphia, county of Philadelphia, and HAROLD VAN DUZEE, residing at 5 Jenkintown, county of Montgomery, State of Pennsylvania, citizens of the United States, have invented certain new and useful Improvements in Valve-Escapements for Reservoirs, Tanks, and Similar Articles, of which 10 the following is a specification.

The object of our invention is to provide a valve escapement which is constructed and adapted to permit of one or more discharges from a tank or reservoir without refilling the 15 same.

In the accompanying drawings, Figure 1 is a vertical section. Fig. 2 is a top view. Fig. 3 is a detail of a two-toothed escapement, and Fig. 4 is a detail of a single-toothed escape- 20 ment.

Same letters indicate similar parts in the different drawings.

A is a flushing tank of any desired construction provided with a flushing or discharge pipe B, leading from box C which in 25 this instance, contains sufficient water for an afterflow, that is allowed to enter the pipe B through the apertures, a. Communication between this box and the body of the tank 30 takes place through the valve seat D, situated directly over the pipe, B, and opened or closed by the valve E, which when closed occupies the position shown in full lines in Fig. 1, and when open is lifted to the position 35 shown in dotted line in Fig. 1.

Stretching across the top of the tank is the bar F upon which all the moving parts are supported as follows: The carriage G extends transversely across the bar F, and is 40 adjustable by slot c and clamped by the bolt b. To prevent lateral swaying of the carriage the rack, d, is provided on the upper surface of the bar F and teeth, e, are provided on the under side of the carriage to mesh with 45 the teeth of the rack. On this carriage is supported the lever, H, pivoted at f. One end of this lever is connected to the valve E before mentioned, and the other end carries an extension piece I to the end of which is attached a chain J. This extension piece I is 50 adjusted so that it may project over the edge

of the tank either at the end as shown in full lines in Fig. 2 or over either side as shown in dotted lines in Fig. 2. When arranged in the desired position by the mechanic in fitting 55 up the tank, the connection is made rigid by turning up the bolt b', which is set through the semi-circular rack d', the teeth of which engage the under side of the lever I and prevent lateral movement. The valve E is normally closed and the lever H, in the position shown in full lines in Fig. 1. When the chain J is pulled the lever H and the valve E are raised into the positions shown in dotted 60 lines in Fig. 1.

There is nothing novel in the operation of the extension piece and the lever, when once fixed, as thus far described, the novelty consisting in the adjustable connection between the extension piece and the lever, which enables the tank to be more readily fitted by the mechanic to the position which it is intended to occupy with the extension piece projecting from the right or left side of the tank, or straight out from the end. To do 75 this ordinarily requires riveting, soldering, or some other work to be performed by the mechanic in fitting up the tank, whereas in this case, it is simply necessary to turn the extension piece in the desired direction and then 80 screw up the bolt b'. It will be noticed from Fig. 2, that when the extension piece projects straight over the end of the tank, it is pushed in, while when it projects over the side, it is pulled out. This extensibility is attained by 85 having the extension piece run through a slot in the bolt b'.

A peculiar feature of the lever H is the projecting tooth t, the function of which will be hereinafter explained.

The tank is provided with a float K, secured by the bolt b'' to the swinging arm L, which is pivoted by the bolt g to the end of the carriage G, and is thus adapted to rise and fall without disturbing the position of 95 the carriage. When the tank is full to the water line s, the float is in the upper position, shown in dotted lines in Fig. 1. When the tank is half empty and the water only reaches the line s', the float drops to the lower dotted 100 line in position in Fig. 1. When the tank is empty, the float reaches the position shown in

full lines in Fig. 1. The arm L is provided with the slots, *i*, so that the position to which the float is allowed to fall is capable of adjustment by changing the position of the bolt 5 *b''*. To the upper end of the arm L is secured a toothed escapement, M, provided with one or more teeth *t'*. These teeth are shown in detail in Figs. 3 and 4; in one case, as a two-toothed escapement, in the other case as a 10 single-toothed escapement. Almost any desired number of teeth may be employed, the number of teeth depending upon the number of discharges which the tank is required to make with a given quantity of water. These 15 teeth are preferably made with their upper surfaces forming the arc of a circle, of which the pin *g*, is the center; and when more than one tooth is employed a space *v*, Fig. 3, should be left between each two teeth sufficiently 20 large to let the tooth *t*, of the lever H, drop through said space. The under side of the tooth, *t*, is preferably concave to fit the convex surface of the teeth *t'*.

The operation of our improved flushing tank 25 is as follows: The tank being full to the line *s* and the valve E, being closed, the ball-float K resting in the upper position shown in dotted lines in Fig. 1, the tooth *t*, of the lever H, is below the teeth *t'* of the arm L. 30 A pull is now given to the chain J and the lever H and valve E are thereby raised into the position shown in dotted lines in Fig. 1. The tooth *t* in its upward motion, finding the first tooth *t'* of the arm L in its way, pushes 35 it aside, thereby raising the arm L and the float K slightly. As soon as the tooth *t* has risen high enough to clear the teeth *t'*, the float K and arm L fall back by their own weight till the ball rests upon the surface of 40 the water in the tank. The chain J being released, the lever H and the valve E, tend to fall by their weight to shut off the flushing pipe B, but are prevented therefrom by the under side of the tooth, *t*, in its downward 45 motion coming against the convex upper surface of the first tooth *t'*, upon which it therefore rests and the valve is thereby held open. As the water is all this time running out through the flushing pipe, B, the float K, falls 50 with the water. This motion draws the convex surface of the tooth *t'* from under the tooth *t*, and when the space *v*, Fig. 3, is reached, the tooth *t* falls through it and allows the lever H, and the valve E to fall and rest upon 55 the valve-seat D, thus stopping any further flow from the body of the tank and leaving all conditions ready for the next operation. The water in the box C thereupon escapes through the openings, *a*, into the flushing 60 pipe B. The float K has reached the middle position shown in Fig. 1 and the water has dropped to the line *s'*. This position brings the second tooth *t'* in position to be displaced by the tooth *t*, when the latter is raised by 65 a second pull of the chain J, when the process of suspending the lever H and valve E by the convex upper surface of the tooth *t'* is

repeated. Should but two teeth *t'* be provided, the tank will have been emptied by the time the valve E is allowed to fall for the 70 second time upon the valve seat D; but as before stated, if it is desired to make a tank full of water, serve for more than two discharges a corresponding number of teeth *t'* will be provided and the devices adjusted accordingly. Should the tank be refilled at any time after one or more discharges the float K will rise to its initial position in the usual way, and the toothed escapement, M, will also be restored to its initial position with the 80 first tooth *t'* in the path of the tooth *t*.

It is obvious that a displacement of the escapement M and with it the float supporting arm L, to which said escapement is secured, is required, to allow the passage of the tooth *t* on the valve-operating lever H, not only in its downward motion to close the valve, but also in its upward motion, as the escapement must be back in the path of the tooth, *t*, after the said tooth has finished its upward motion. 90 Otherwise, there would be nothing to hold up the valve operating lever H, and the valve E would close at once. It is obvious that when it is desired to have the same amount of water give more than two discharges, its escapement will require additional teeth *t'*, until their number corresponds to the number of discharges required. It is obvious also that if it is desired to vary the volume of water to be discharged by a given escapement, the bolt *b''* must be changed to some other of the slots *i* in the float supporting arm, thereby changing the proportion between the distance from center pin to the surface of teeth of escapement and the distance from center pin to center of float. 95

We claim—

1. A flushing tank or other reservoir, provided with a float mounted upon a swinging arm, the upper end of which carries a toothed escapement, a lever operated by the pull-rod and carrying a tooth which controls the action of said toothed escapement, and with a valve, the closing of which is controlled by the movement of the teeth of said escapement, substantially as shown and for the purposes specified. 110

2. A flushing tank or other reservoir, provided with a valve operating lever mounted upon a suitable carriage, a swinging extension piece adjustably connected with said lever and a semi-circular rack, the teeth of which engage the under side of said extension piece, whereby lateral movement thereof is prevented, substantially as shown for 115 the purposes specified. 120

3. A flushing tank or other reservoir, provided with a valve operating lever mounted upon a suitable carriage, and with a tooth projecting therefrom, a float supporting arm pivoted to said carriage and a toothed escapement mounted upon said float supporting arm in the path of the tooth on said valve operating lever, whereby said valve operating lever 130

is prevented from rising or falling, until said toothed escapement is displaced, substantially as described and specified.

4. An escapement for controlling the closing of the valve of a flushing tank or other reservoir, which consists of a float supporting arm, having one or more teeth thereon and a valve operating lever, having one or more teeth thereon, adapted to engage with the teeth on said arm both in the up and down

movements of said lever, whereby said movements are prevented, until said escapement is displaced by the motion of said float supporting arm substantially as shown, and for the purposes specified.
